INSTRUMENT FOR CHECKING TOLERANCES OF WORK-PIECES

Wilhelm Haug, Mulhouse, France, assignor to Manufacture de Machines du Haut Rhin, Mulhouse-Bourtzwiller, France

Application July 17, 1951, Serial No. 237,240

Claims priority, application France January 10, 1951

4 Claims. (Cl. 200—61.41)

The present invention relates to a precision gauging instrument by means of which it is possible not only to verify that the prescribed tolerances of a machined work-piece are maintained, but also to determine, at the same time, whether the gauged dimensions are within one or another of a plurality of predetermined limits.

This instrument is employed in combination with means suitable for rendering visible the results of gauging, that is with a luminous indicator.

The necessity of producing great numbers of precision work-pieces with very small tolerances has led to the setting up of classifications. Work-pieces are classified into a convenient number of small groups established according to the precision required for a faultless operation of the pieces.

The electro-mechanical gauging instrument according to the present invention is intended to reduce the duration of the gauging operation. Besides doing away with clearances required by previous mechanical gages, which gauges because of their rapid wear, have to be frequently renovated, the instrument of the present invention permits of a considerable saving of time.

This gauging instrument is represented by way of example in the accompanying drawings:

Figs. 1, 2, 3 show diagrammatically in elevational view various stages of the working of the controlling arm of the instrument;

Fig. 4 shows the circuit arrangement of the instrument.

The controlling arm E, employed according to the present invention, distinguishes itself from the controlling arms heretofore known and operating in analogous ways, by a leaf-spring F additionally mounted on the controlling arm E which carries contacts G₁ cooperating with fixed contacts A, C; this leaf-spring F carries contacts G₂ and is so constructed that feeble pressures are sufficient to move it away from its vertical position of rest. As opposed contacts B, D for the contacts G₂ of the leaf-spring, use is made of two further contact-screws arranged in an appropriate way. This arrangement is operatively combined, according to the accompanying wiring diagram shown in Fig. 4, with a luminous contact indicator in such a way that, as long as the controlling arm and the leaf-spring are in the mean position shown in Fig. 1, the "white" lamp, placed in the middle of the luminous indicator, is lit up. For the sake of clarity, the lamp that lights up to indicate actual position is, surrounded with a thick line in Figs. 1, 2 and 3.

The contacts G₁ of the controlling arm are replaced in Fig. 4 by a switch triangle H₁. This triangle is equilateral and is made of conductive material. The increase, thus obtained, in the scope of regulation is considerable and of importance for the compactness of the instrument. The operations is as follows:

If, for example in the gauging of a given work-piece, the controlling arm E is moved away from its mean position (Fig. 1), contact occurs first between the contact G₂ or H₂ of leaf-spring F with the corresponding

2

contact screw B (Fig. 2). Then the relay S is energized and lever s swings to the left. The corresponding lamp which is, for example, bichromatic (white and red) lights up whereas the central lamp (white) is extinguished (see also Fig. 2). If the displacement of the controlling arm is greater, the contact G₁ or H₁ comes into contact with the opposed contact A (Fig. 3). The relay R is energized and consequently the lever 2^r swings to the left. The corresponding monochromatic (for example: red) lamp lights up, whereas the bichromatic lamp is extinguished (Fig. 3). As the contact screws (A, B, C, D in Fig. 4) have their ends adjusted to the desired tolerance stages, both ignition and extinction of the lamps alway occur at the very instant when a limit of said stage is crossed.

Each lamp, therefore, corresponds to a stage or section of the total tolerance, so that work-pieces, which correspond to the same color, belong to the same tolerance group.

What is claimed is:

1. In a gauging instrument, in combination, stationary supporting means; a movable rigid body being mounted to said stationary supporting means for movement dependent on the dimensions of an article to be gauged; a resilient strip-shaped member secured at one end thereof to said movable rigid body so as to be displaced by a movement of the same; a first movable contact fixedly secured to said movable rigid body; a second movable contact arranged at the other end of said resilient member; a first stationary contact mounted on said stationary supporting means and being adapted to cooperate with said first movable contact, said first movable contact being normally arranged at a distance from said first stationary contact; and a second stationary contact electrically insulated from said first stationary contact and mounted on said stationary supporting means and being adapted to cooperate with said second movable contact, said second movable contact being arranged normally at a distance from said second stationary contact being smaller than the distance between said first movable contact and said first stationary contact whereby at a small movement of said rigid body in one direction only said second movable contact arranged at said other end of said resilient member and said second stationary contact make contact with each other, said first stationary contact and said first movable contact secured to said movable rigid body being separated from each other, whereas at a greater movement of said rigid body in said one direction both said first and second movable contacts make contact, respectively, with said first and second stationary contacts, said resilient member assuming a curved shape thereby.

2. In a gauging instrument, in combination, stationary supporting means; a movable rigid arm being pivoted to said stationary supporting means for rotation dependent on the dimensions of an article to be gauged; a resilient strip-shaped member secured at one end thereof to said movable rigid arm so as to be displaced by a rotation of the same about the pivot thereof; a first movable contact fixedly secured to said movable rigid arm; a second movable contact arranged at the other end of said resilient strip-shaped member; a first stationary contact mounted on said stationary supporting means and being adapted to cooperate with said first movable contact, said first movable contact being normally arranged at a distance from said first stationary contact; and a second stationary contact electrically insulated from said first stationary contact and mounted on said stationary supporting means and being adapted to cooperate with said second movable contact, said second movable contact being arranged normally at a distance from said second stationary contact being smaller than the distance between said first movable contact and said first stationary contact whereby at

a small rotation of said rigid arm about the pivot thereof in one direction only said second movable contact arranged at said other end of said resilient strip-shaped member and said second stationary contact make with contact with each other, said first stationary contact and said first movable contact secured to said movable rigid arm being separated from each other, whereas at a large rotation of said rigid arm about the pivot thereof in said one direction both said first and second movable contacts make contact, respectively, with said first and second stationary contacts, said resilient strip-shaped member assuming a curved shape thereby.

3. In a gauging instrument, in combination, stationary supporting means; a movable rigid arm being pivoted to said stationary supporting means for rotation dependent on the dimensions of an article to be gauged; a resilient strip-shaped member secured at one end thereof to said movable rigid arm so as to be displaced by a rotation of the same about the pivot thereof; a first movable contact fixedly secured to said movable rigid arm; a second movable contact arranged at the other end of said resilient strip-shaped member; a first stationary contact mounted on said stationary supporting means at one side of said first movable contact and being normally arranged at a distance therefrom; a second stationary contact electrically insulated from said first stationary contact and mounted on said stationary supporting means at one side of said second movable contact and at the same side as said first stationary contact, said second movable contact being arranged normally at a distance from said second stationary contact being smaller than the distance between said first movable contact and said first stationary contact; a third stationary contact mounted on said stationary supporting means at the other side of said first movable contact and being normally arranged at a distance therefrom; a fourth stationary contact electrically insulated from said third stationary contact and mounted on said stationary supporting means at the other side of said second movable contact and at the same side as said third stationary contact; said second movable contact being arranged normally at a distance from said fourth stationary contact being smaller than the distance between said first movable contact and said third stationary contact whereby at a small rotation of said arm about the pivot thereof in any direction said second movable contact arranged on said other end of said resilient strip-shaped member makes contact with one of said second and fourth stationary contacts, said first and third stationary contacts being separated, respectively, by distances from said first movable contact, whereas at a large rotation of said arm about the pivot thereof both said first and second movable contacts make contact, respectively, with one of said first and third stationary contacts and one of said second and fourth stationary contacts, said resilient strip-shaped member assuming a curved shape thereby.

4. In a gauging instrument, in combination, stationary supporting means; a movable rigid arm being pivoted to

5 said stationary supporting means for rotation dependent on the dimensions of an article to be gauged; a resilient strip-shaped member secured at one end thereof to said movable rigid arm so as to be displaced by a rotation of the same about the pivot thereof; a first movable contact fixedly secured to said movable rigid arm and being shaped as a triangle having a base substantially at right angles to said rigid arm and a vertex forming the end of said rigid arm carrying said resilient strip-shaped member; 10 a second movable contact arranged at the other end of said resilient strip-shaped member; a first stationary contact mounted on said stationary supporting means at one side of said first movable contact and being normally arranged at a distance therefrom; a second stationary contact electrically insulated from said first stationary contact and mounted on said stationary supporting means at one side of said second movable contact and at the same side as said first stationary contact, said second movable contact being arranged normally at a distance from said second stationary contact being smaller than the distance between said first movable contact and said first stationary contact; a third stationary contact mounted on said stationary supporting means at the other side of said first movable contact and being normally arranged at a distance therefrom; a fourth stationary contact electrically insulated from said third stationary contact and mounted on said stationary supporting means at the other side of said second movable contact and at the same side as said third stationary contact, said second movable contact being arranged normally at a distance from said fourth stationary contact being smaller than the distance between said first movable contact and said third stationary contact whereby at a small rotation of said arm about the pivot thereof in any direction said second movable contact arranged on said other end of said resilient strip-shaped member makes contact with one of said second and fourth stationary contacts, said first and third stationary contacts being separated, respectively, by distances from said first movable contact, whereas at a large rotation of said arm about the pivot thereof both said first and second movable contacts make contact, respectively, with one of said first and third stationary contacts and one of said second and fourth stationary contacts, said resilient strip-shaped member assuming a curved shape thereby.
